UNITED STATES PATENT OFFICE.

ELMER VAN DUSEN, OF STRATFORD, CONNECTICUT.

CONE WINDER WITH THREAD-SEVERING ATTACHMENT.

Application filed October 29, 1923. Serial No. 671,314.

To all whom it may concern:

Be it known that ELMER VAN DUSEN, a citizen of the United States, and resident of Stratford, in the county of Fairfield and 5 State of Connecticut, has invented certain new and useful Improvements in Cone Winders with Thread-Severing Attachments, of which the following is a specification.

10 This invention relates to a cone winder, and has more particular reference to a machine for winding a thread of yarn, as from a cop or jack bobbin to a winder bobbin, equipped with an attachment for severing the thread should the same become accidentally removed from its guide.

Ordinarily, yarns for knitting arrive at the knitters on cops or jack bobbins, and to facilitate knitting are wound off on a 20 much larger bobbin, called a winder bobbin. Great care must be taken to have the yarn in the best possible condition on these winder bobbins, as this winding is the last handling of the yarn before it goes into the 25 needles on the knitting machine. With certain types of cone winders now in use, the thread of yarn as it is being wound off of a cop or jack bobbin onto a winder bobbin frequently becomes displaced from its guide, 30 usually a porcelain guide movable with the building rail, to wind irregularly, alternately upon said winder bobbin at locations below those which should receive the thread, and beneath the same upon the bobbin spindle. Naturally, such winding of the thread 35 of yarn renders the yarn upon the winder bobbin unfit for presentation to a knitting machine. The whole of, or a large portion of, the strand or thread must be removed 40 and properly rewound. The present invention purposes to preclude the possibility of improper winding of the thread of yarn by reason of the thread leaving its guide.

It is, therefore, an object of the invention 45 to equip a machine of the character mentioned with means for severing a thread of yarn being wound as soon as said thread has become removed from its guide, in order that there can be no further winding of the 50 thread upon a bobbin or the like until an operator has tied together the severed ends of thread and replaced the same in its guide.

It is a further object of the invention to

equip cone winders having thread guides movable with their building rails with 55 thread severing attachments adapted to cause threads of yarn being wound to be cut or broken should said threads become removed from their guides to thus preclude further winding of yarn until the severed ends of thread are joined and the thread is reinserted in its guide.

With the above and other objects in view, the invention comprises the construction, arrangement and combination of parts as now 65 to be fully described and as hereinafter to be specifically claimed, it being understood that the disclosure herein is merely illustrative and meant in no way in a limiting sense, changes in details of construction and arrangement of parts of the thread severing attachment and its association with the winding machine, and in details of construction and arrangement of parts of the machine for winding a bobbin or the like, 70 being permissible so long as within the spirit of the invention and the scope of the appended claims.

In the accompanying drawing forming 75 a part of this specification,

Fig. 1 is an end elevation, partially broken away, of an ordinary cone winder of commerce, shown equipped with a thread severing attachment incorporating the features of the invention;

Fig. 2 is a sectional, elevational diagrammatic view, parts being broken away and other parts being not shown, disclosing the means for rotating the winder bobbins and for accomplishing the building motion, etc., 90 of the cone winder of Fig. 1, and illustrating the novel thread severing attachment in its proper relation to said cone winder;

Fig. 3 is a fragmentary elevational view, on an enlarged scale, detailing the thread 95 severing attachment and its relation to the winder bobbin and remainder of the cone winder;

Fig. 4 is a fragmentary end sectional view, approximately corresponding with the 100 showing of Fig. 3, further detailing the severing attachment and its relation to the machine;

Fig. 5 is an elevational view, on a still 105 larger scale, of a fragment of the severing attachment;

Fig. 6 is an end view of said attachment; and

Fig. 7 is a top plan view of a fragment thereof.

5 I have preferred to show the invention applied to an ordinary thread winding machine of commerce, known as a Payne cone winder.

Of said cone winder, 10 and 11 denote 10 end members, and 12 and 13 denote, respectively, upper and lower side members, of a rectangular machine frame, the upper and lower side members being connected to the end members in any suitable fashion.

15 Numeral 14 represents spaced apart strips of boarding extending longitudinally across the top of the machine frame, and 15 represents similar strips arranged beneath the strips 14, in which strips vertical bobbin 20 spindles 16, extending upwardly beyond the strips 14, are mounted. 17 is a receiving shaft beneath the strips 14 and above the strips 15, and preferably half-way between the sides of the machine, arranged longitudinally of the frame and mounted in the end members 10 and 11 to extend beyond said end members. 18 denotes power receiving pulleys upon the receiving shaft and beyond the end member 10, and 19 denotes 30 band pulleys for driving the spindles 16, each of said spindles having a pulley 20 receiving a banding 21 traveling over a band pulley 19. Each band pulley, as disclosed, has a double groove, to drive a spindle 16 35 on either side of the machine. 22 are winder bobbins removably situated upon the upper ends of the spindles 16, above the strips 14, to be individually stopped when this is desirable, and each winder bobbin can have 40 its own stop motion (not shown) to cease winding when filled with thread of yarn.

At the end of the receiving shaft 17 opposite the power receiving pulleys and beyond the end member 11, is a receiving pulley 23, for transmitting power to the building motion inside the lower part of the machine as in Figs. 1 and 2. A belt 24 passing over the pulley 23 also passes over a pulley 25 on a shaft 26 outside the end frame and mounted in the end member 11 in any suitable manner. A pinion 27 on said shaft 26 meshes with a gear 28 on a jackshaft 29, also outside the end frame and mounted in the end member 11. A 50 double pinion gear 30 on said jackshaft 29 and within the frame meshes with a double gear 31 on a shaft 32 suitably mounted in the frame so that the teeth of one pair of gears are just half the distance of one tooth ahead of the other pair—this to lessen backlash.

Upon the shaft 32 is a heart cam 33 adapted to impart to the building rail 34 a slow rising movement, making a close wind on the bobbin, and a quick falling movement

which lays the yarn across the close wind and binds it to the winder bobbin. The lifting rail, see Figs. 1 and 2, is connected with the heart cam in the following manner. By action of the cam, a lever 35 on a rock-shaft 36 parallel to the shaft 32, is made to transmit its motion by means of a chain belt 37 attached to said lever 35 and running over an idler wheel 38, to connect said lever with a second lever 39 on a rockshaft 40 at right-angles with the shaft 32. On this rockshaft 40 other levers, denoted 41, are connected by upright rods 42 to the building rail to give to said rail a rise and fall preferably corresponding to the height of the cone-shaped portion of the winder bobbin. On another lever 43 of the rockshaft 40 is a ball weight 44 to equalize the motion, balance the weight of the building rail, to relieve the heart cam of excessive weight when lifting the rail. The first upright rods to the building rail are, as shown, near one end of the machine. The rockshaft 40 with lifting rods and ball counter weight can consequently be duplicated to manipulate all other upright rods 42, the rockshafts 40 having levers 45 connected by links 46. The upright rods 42 are desirably not connected with the levers 41, but each has a broad heel 47 to ride easily on a small roller wheel (not shown) in the ends of the levers.

The building rail 34 may be secured to the upright rods 42 in any suitable manner, as denoted generally at 48, preferably to be separately adjustable on each of said upright rods.

The cops are shown placed in their proper positions just under the cotton friction or cleaner rails 50 mounted at either side of the frame adjacent the upper side members 12 and extending longitudinally of the machine. The yarn is adapted to pass from a cop through the inside curl of a double whirl guide wire (not shown), then through an outer curl 51, over a felt 52 and through a porcelain pot eye guide 53, said curl, felt and eye guide all being upon the cleaner rail 50, and then to a porcelain guide 54 attached to a friction cup 55 on a screw spindle 56 extending upward from the building rail, to be thrown around a cloth covered part (not shown) of the winder bobbin to which it clings and thereby gets its start.

The friction cups 55 may be associated with the screw spindles 56 in any approved manner, to control the diameter of the bobbin. As shown, when the yarn builds the bobbin to the required diameter at its base the yarn rubs the cup to move it around and up on the screw spindle, as is well understood in the present art.

The porcelain guides 54 are attached to the friction cups as by means of wires 57, to move upwardly or downwardly with said cups, but said guides 54 are fixed against

movement of rotation, as by means of extensions 58 of said wires, each extension having a loop surrounding a vertical stay rod 59 on said building rail adjacent said screw spindles.

As long as the threads of yarn pass over the porcelain guides 54 movable with the cups, during each successive reciprocation of the building rail said yarn does not wind on the winder bobbins as far down as it did on the preceding reciprocation. That is, a cup and the yarn with it move up gradually until the bobbin is full to the top of the spindle, preferably leaving the top 15 in the shape of a cone just as it has built it all the way up.

If desired, the building rail can be given, and usually is given, endwise reciprocation during its vertical reciprocation in order that the yarn may not run in one crease on the felt 52 upon the cleaner rail 50.

In the machine well known and briefly described, the thread of yarn as it is being wound off of a cop onto a winder bobbin frequently becomes displaced from its porcelain guide 54 to thereafter travel over the building rail 34 so that the thread is wound alternately upon the winder bobbin at locations below those intended to receive the thread, and beneath said winder bobbin, upon its spindle, thus ruining the wound bobbin for its intended purpose. To obviate this difficulty, I provide thread severing attachments 60 adapted to extend the full length of the machine, from end to end thereof, and I preferably secure said attachments to the inner faces of the building rails 34, as by means of the screws 62.

As very clearly shown, each severing attachment includes preferably saw shaped teeth 63 which protrude upwardly beyond the building rail and desirably outwardly away from the winder bobbins. Clearly, should a thread of yarn become removed from a porcelain guide 54 during the winding operation, as shown by the dotted line in Fig. 4, it will immediately be drawn against a tooth 63 of the severing attachment which will act as a guide to turn the thread into one of the slots between the teeth, these slots being tapered to pinch the thread and thus cut or break it as the winder bobbin rotates to stretch the thread tight. Naturally, there can be no further winding of the thread until the severed ends are connected. To connect the ends the operator releases the winder bobbin from its spindle, and after the tie is made, reinserts the thread of yarn into its guide 54 and allows the bobbin to again turn with its spindle.

It is to be understood that the teeth 63 of the severing attachment need not be of the exact construction shown. For example, certain teeth can project toward the right as disclosed in Fig. 5, while others pro-

ject toward the left, depending upon whether the bobbin is being wound from left to right or vice versa, the idea being to provide severing teeth best adapted to their purposes.

It is to be further understood that while I have shown the invention applied to a Payne cone winder, it is applicable to other styles and types of winding machines. Furthermore, the severing attachments need not be carried upon the building rails as illustrated and described, but may be otherwise associated with the particular machine disclosed or with machines of different types in connection with which said attachments would be useful to be movable with, or not movable with, the thread guides, as preferred.

Having thus fully described the invention, what I claim as new and desire to secure by Letters Patent is:

1. In a machine for winding a strand of thread, a thread guide, and means for severing said strand when the thread becomes removed from its guide.

2. In a machine for winding a strand of thread, a roll adapted to receive said thread, a thread guide, and means for severing said strand when the thread becomes removed from its guide.

3. In a machine for winding a strand of thread, a roll adapted to receive said thread, a device for building up layers of thread upon said roll, a thread guide movable with said device, and means for severing said strand when the thread becomes removed from its guide.

4. In a machine for winding a strand of thread, a rotating roll adapted to receive said thread, a reciprocatable device for building up layers of thread upon said roll, a thread guide movable with said device, and means for severing said strand when the thread becomes removed from its guide.

5. In a machine for winding a strand of thread, a thread container, a rotating roll adapted to draw thread from the container, a thread guide, and means for severing said strand when the thread becomes removed from its guide.

6. In a machine for winding a strand of thread, a thread container, a rotating roll adapted to draw thread from the container, a device for building up layers of thread upon the rotating roll, a thread guide movable with said device, and means for severing said strand when the thread becomes removed from its guide.

7. In a machine for winding a strand of thread, a thread container, a roll adapted to draw thread from said container, a reciprocatable device for building up layers of thread upon said roll, means for rotating said roll and for reciprocating said device, a thread guide movable with said device,

and means for severing said strand when the thread becomes removed from its guide.

8. The combination as specified in claim 5, wherein said means consists of a severing attachment lying in the normal path of said thread when it leaves its guide.

9. The combination as specified in claim

7, wherein said means consists of a severing knife lying in the normal path of said thread when it leaves its guide. ¹⁰

Signed at Bridgeport, in the county of Fairfield, and State of Connecticut, this 25th day of October, A. D., 1923.

ELMER VAN DUSEN.
